H. A. W. SMITH,

RERAILER,

APPLICATION FILED JAN. 13, 1919.

1,305,626.

Patented June 3, 1919.

UNITED STATES PATENT OFFICE.

HENRY A. W. SMITH, OF CHATHAM, VIRGINIA, ASSIGNOR OF ONE-HALF TO EDWIN S. REID, OF CHATHAM, VIRGINIA.

RERAILER.

1,305,626.

Specification of Letters Patent. Patented June 3, 1919.

Application filed January 13, 1919. Serial No. 270,911.

To all whom it may concern:

Be it known that I, HENRY A. W. SMITH, a citizen of the United States, residing at Chatham, in the county of Pittsylvania and 5 State of Virginia, have invented a new and useful Rerailer, of which the following is a specification.

One object of this invention is to provide a rerailer which may be turned end for end 10 and upside-down thereby rendering the rerailer effective regardless of whether the car to be railed moves from left to right or from right to left. Another object of the invention is to provide novel means whereby 15 the rerailer may be adjusted or swung in a substantially horizontal plane and be held in adjusted positions. A further object of the invention is to supply a rerailer which may be extended to any desired length there- 20 by making it possible to shift a car through a long distance, even from one track to an adjoining track, or from one track to a third track, over an intermediate track.

Within the scope of what is claimed, a 25 mechanic may make changes without departing from the spirit of the invention or placing the utility of the invention in jeopardy.

In the drawing:—Figure 1 shows the rerailer in top plan, assembled with a track; 30 Figs. 2, 3, 4 and 5 are sections taken, respectively, on the lines 2—2, 3—3, 4—4 and 5—5 of the drawings; and Fig. 6 is a section on the line 6—6.

The numerals 1 and 2 denote the rails of 35 a track. A member 3 is provided, the same including a supporting arm 4 and a guiding arm 5 disposed at an obtuse angle to the supporting arm, the arms merging into a head 6 adapted to rest as shown at 7 on 40 the flange of the rail 1 and to abut as shown at 8 against the ball of the rail. The arm 5 has a guiding groove 9 extended at 10 into the head 6, the head being cut away at 11, at the inner end of the groove, so that the 45 flange of a car wheel, having traversed the groove, may coöperate with the inner edge of the ball of the rail 1, in a way in which those skilled in the art will understand.

The rerailer includes a member 12 having 50 a supporting arm 14 and a guiding arm 15, the arms being connected by a head 16. There is a guiding groove 17 in the arm 15, the groove merging into an elevated surface

18 adapted to pass the flange of a car wheel over the ball of the rail 2, to coöperate with 55 the inner edge of the ball.

It is to be observed that the parts 9, 10 and 11 which are formed on the upper surface of the member 3, are duplicated upon the lower surface of the member 12, where- 60 as the parts 17 and 18 which exist on the upper surface of the member 12, are duplicated on the lower surface of the member 3. Consequently, the members 3 and 12 may be turned upside-down and end for end, 65 thereby making it possible to railed a car by moving the car either to the right or to the left, the rerailer being set in Fig. 1 to railed a car which is to be moved to the left. 70

Any desired number of extensions 19 may be connected, by means of fish plates and bolts 20, or otherwise, with the guiding arms 5 and 15. The terminal extensions 21 have flared inlet mouths. The rerailers may be 75 spiked to the ties as shown at 23, wherever necessary, and the terminal extensions 21 may be supplied with depending prongs 24 which will serve as a holding and sustaining means under some circumstances. Since 80 the members 3 and 12 of the rerailer may be elongated to any desired extent, a car may be shifted from one track to an adjoining track, or even be moved from one track across several tracks to a relatively remote 85 track.

The heads 6 and 16 of the rerailer members are supplied with longitudinal ribs 25, lugs 26 projecting from the members, beyond the ribs, the lugs being disposed intermediate the ends of the ribs. In the outer surfaces of the heads 16 and 6, seats 27 are formed, the same being adapted to coöperate with screws or other like elements in clamps 29 having hooks 30 coöoperating with 90 the flanges of the rails 1 and 2. Wedges 31 may be inserted between the web of the rails and either end of the ribs 25, it being possible to shift the clamps 29 longitudinally of the heads 6 and 16—all of which will be 95 understood when Fig. 4 is examined. The wedges 31 may be advanced or retracted, thus to vary the angle between the arms 5 and 15 and the respective rails and by locating the clamps 29 properly and by tight- 100 ening up the screws 28, the rerailed mem-

bers may be held in any position to which they may have been adjusted horizontally through the instrumentality of the wedges.

I claim:

- 5 1. A rerailer comprising a pair of members having laterally extended guiding grooves in their upper surfaces, one member being cut away at the inner end of its groove to permit the flange of a car wheel to 10 coöperate with the inner edge of one rail of a track, the groove of the other member merging into an elevated part permitting the flange of a car wheel to ride over the other rail of a track and coöperate with the inner 15 edge thereof, each member, upon its lower surface, duplicating the construction of the other member, whereby the members may be turned end for end and upside-down, there-

by rendering the rerailer effective when the rerailing operation is carried out in opposite 20 directions.

2. A rerailer comprising a member having a guiding groove and supplied intermediate its ends with a rail-engaging fulcrum lug; a rail-engaging wedge coöoperating with said member at one side of the lug to effect an adjustment of the member in a substantially horizontal plane; and a rail-engaging clamp coöoperating with said member.

In testimony that I claim the foregoing 30 as my own, I have hereto affixed my signature.

HENRY A. W. SMITH.
